Des. 229,366

Patented Nov. 20, 1973

229,366

COMBINED SET OF TOOLS AND CARRYING CASE THEREFOR

Everett R. Yonce, 259 E. 12th St., Oakland, Calif. 94606

Filed May 3, 1971, Ser. No. 139,998

Term of patent 14 years

Int. Cl. D3—02

U.S. Cl. D87—1 R

FIG. 1

FIG. 2

FIG. 3

FIG. 4

FIG. 5

FIG. 1 is a perspective view of the interior of combined set of tools and carrying case therefor showing my new design;

FIG. 2 is a similar view to FIG. 1 but showing one hinged panel in open position;

FIG. 3 is a similar view to FIG. 1 but showing the second hinged panel in open position;

FIG. 4 is a top plan view showing both hinged panels in an open position; and

FIG. 5 is a view showing the side opposite that seen in FIG. 1 but on a reduced scale.

I claim:

The ornamental design for a combined set of tools and carrying case therefor, substantially as shown.
